GARMENT SUPPORTING DEVICE

Abraham Levine, Elizabeth, N. J., assignor to
Presto Lock Corporation, Brooklyn, N. Y.Original application April 16, 1936, Serial No.
74,675. Divided and this application March
29, 1937, Serial No. 133,525

5 Claims. (Cl. 312—177)

This application is a division of my co-pending application Serial Number 74,675, filed April 16, 1936.

This invention relates to improvements in garment supporting devices for use in traveling bags and the like.

There are now being provided in traveling bags, garment supporting devices which usually are pivotally attached to the cover of the bag, 10 or to the back wall of the body of the bag adjacent the hinge connection between the cover and the body. The supporting devices are designed to lie within the cover when the bag is closed; and such devices in many instances are provided 15 with means for supporting a plurality of garment hangers or rods loosely so that they can be readily removed from the supporting device for the purpose of draping garments thereon. In order to prevent the garments from falling off 20 of the hangers when the bag is closed, means are provided to prevent accidental removal of the hangers. However, such means as heretofore provided, have been found relatively difficult to manipulate inasmuch as they involved a somewhat 25 complicated structure, which also increased the cost of manufacture thereof.

It is, therefore, an object of this invention to provide a garment supporting device for traveling bags having simple, inexpensive and easily 30 manipulated means for retaining garment hangers on the support to prevent the hangers from falling off of the support when the bag is closed.

This and other objects are attained by the novel construction, combination and arrangement 35 of parts hereinafter described and shown in the accompanying drawing, constituting a material part of this disclosure, and in which:

Fig. 1 is a perspective view of a garment supporting device embodying my invention.

Fig. 2 is a perspective view of means for retaining garment hangers on the support.

Fig. 3 is a side elevational view, in section, showing one position of the hanger retaining means.

Fig. 4 is a fragmentary view showing one end of a garment hanger used with the support.

Fig. 5 is a side elevational view, in section, showing another position of the hanger retaining means.

Fig. 6 is an elevational view, partly in section, showing details of the hanger retaining means.

Fig. 7 is a fragmentary view of another form of garment hanger adapted to be used with the support and forming a part of this invention.

Referring to the drawing, in Fig. 1, the gar-

ment support is shown in an extended condition for draping garments thereon. The support comprises a pair parallel bars 7, having one end thereof adapted to be pivotally connected to the cover or the body of the traveling bag adjacent the hinge connection between the body and cover. The bars 7 are braced by a bar 8; and each bar is provided with a projection 9 adapted to engage projections (not shown) within the body of the bag to hold the bars 7 in a horizontal position when the support is extended as shown in Fig. 1. Pivotally connected to the outer ends of bars 8 are upwardly extending bars 10 which are inclined forwardly at an angle to the vertical. The lower ends of bars 10 are bent under bars 7 and engage the latter to limit the forward inclination of bars 10. The bars 10 are braced by a bar 11, which also serves as means over which garments can be folded when the support is collapsed and positioned in the cover of the traveling bag. The bars 10 are further braced by a bar 12 adjacent the upper ends thereof.

A U-shaped member 15 having legs 13 is removably attached to the upper ends of bars 10 by means of projections 14 from the legs 13 passing through apertures in bars 10.

Attached to the member 15, adjacent the legs 13, are tubular members 17, having slidably mounted therein rods 21, having heads 23. Encircling the rods 21, and positioned between the members 17 and the heads 23, are coiled compression springs 22, which normally tend to eject the rods from the tubular members. The rods 21, at the ends opposite to the ends carrying the heads 23, are provided with a reduced portion 19, and a tapered nose 20. Ejection of the rods from the tubular members is prevented by the engagement of the nose 20 with an internal shoulder 33 in the tubular member.

Slidably mounted vertically on the member 15 are flat casings 16 having apertures 18 through which the noses 20 of rods 21 pass. The casings 16 are normally maintained in a raised position by bowed springs 24, or similar means, positioned between the upper walls of the casing and the upper surface of member 15, so that normally the apertures 18 are eccentric of the tubular members 17. The lower edge of the casing surrounding the aperture 18 has a sharp edge 31, which is adapted to engage the flat rear surface of nose 20 when the rod 21 is forced through the member 17, to prevent the spring 22 from retracting the rod to the position shown in Fig. 5.

The tubular members 17 are adapted to sup-

port a plurality of garment hangers 25, each of which is provided at the ends thereof with open annular members 26, the space between the free end of each member 26 and the hanger 25 being less than the diameter of the tubular member 17, so that the hanger cannot be removed from the tubular member.

In operation, to release the noses 20 from engagement with the sharp edges 31 on casings 16 10 at the lower border of apertures 18, the casings are pressed downward (see Fig. 5) against the action of springs 24, to position the apertures 18 concentric with the tubular members 17. The rods 21 are then rapidly ejected by the coiled 15 springs 22. Garment hangers can now be mounted on rods 21, as the space between the free end of each member 26 and the hanger 25 is greater than the diameter of rods 21. The garment hangers can now be shoved over tubular members 17, and the rods 21 pushed inwardly until the noses 20 snap over the edges 31. The hangers can not now be removed from the members 17, until the casings 16 are depressed to release the noses 20.

25 In Fig. 7 is shown another form of garment hanger 25, having a member 39 encircling partially the tubular member 17, the member 39 having the free end 34 thereof outwardly directed and positioned beneath the leg 13, which 30 obviously prevents upward movement of the garment hanger. Garment hangers of this form must be positioned on the tubular members 17 in the same manner as above described. When the form shown in Fig. 7 is used, elements 13 and 35 17 should be of substantially the same length.

The foregoing disclosure is to be regarded as descriptive and illustrative only, and not as restrictive or limitative of the invention, of which 40 obviously an embodiment may be constructed including modifications without departing from the general scope herein indicated and denoted in the appended claims.

Having thus described my invention, what I 45 claim as new and desire to secure by Letters Patent, is

1. In a garment supporting device, a U-shaped member, tubes mounted on the U-shaped member parallel to and adjacent the legs thereof, rods slidably mounted in said tubes, each of said rods 50 having a reduced portion and a tapered nose at one end and a head at the other end thereof, compression springs encircling said rods and positioned between said heads and tubes to constantly tend to eject the rods from the tubes, 55 means to prevent complete ejection of the rods from the tubes, casings mounted on and slidably transversely of the U-shaped member, said casings having apertures adapted to register with the tubes, and spring means to normally hold 60 said casings in positions so that the apertures

therein will not register with the tube, whereby when the tapered noses on the rods are passed through the casings portions of the casings will snap into the reduced portions of the rods and prevent ejection of the rods.

2. In a garment support, a member, tubes mounted on the member, rods slidably mounted in the tubes, resilient means tending constantly to eject the rods from the tubes, means to limit the extent of ejection of the rods, said rods having one end thereof rounded and provided with notches adjacent said rounded ends, casings slidably mounted on the member and having apertures adapted to register with said tubes, and resilient means normally forcing said casings to 10 positions so that the apertures will not register with the tubes so that when the rounded ends of the rods are forced through said apertures portions of the casings will snap into the notches and prevent ejection of the rods.

3. In a garment support, a member, tubes mounted on the member, rods slidably mounted in the tubes, resilient means tending constantly to eject the rods from the tubes, means to prevent complete ejection of the rods, said rods being provided with notches adjacent one end thereof, plates slidably mounted on said member and having apertures adapted to register with the openings in said tubes, and means normally holding said plates in positions to cause non-register of the apertures and tube openings so that when the rods are moved through said apertures the plates will engage in said notches to prevent ejection of the rods.

4. In a garment support, a U-shaped member, tubes mounted on the member adjacent to and parallel to the legs thereof, rods slidably mounted in the tubes, a clothes hanger, and downwardly opening hooks at the ends of said hanger slidably mounted on the tubes, said hooks having means engaging the legs of said member so that the hanger can be removed only by sliding the hooks on the tubes to positions beyond the free ends of the legs.

5. In a garment support, a member, tubes mounted on the member, rods slidably mounted in the tubes, resilient means tending constantly to eject the rods from the tubes, means to prevent complete ejection of the rods, said rods being provided with notches adjacent one end thereof, plates movably mounted on said member and having openings adapted to register with the openings in said tubes, and means normally holding said plates in positions to cause non-register of the openings in the plates and the tube openings so that when the rods are moved through the openings in the plates the latter will engage in said notches to prevent ejection of the rods.

ABRAHAM LEVINE. 60
